(57) **CLAIM**

The ornamental design for a trigger grip, as shown and described.

DESCRIPTION

FIG. 1 is a perspective view of the trigger grip of this invention;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view of the trigger grip of this invention illustrating the trigger grip ready for gripping;

FIG. 9 is a front view of the trigger grip of this invention with a thrust plate in state of gripping wire; and,

FIG. 10 is a front view of the trigger grip with another thrust plate in state of gripping wire.

The broken lines are for illustrative purpose only and form no part of the claimed design.
